DESIGN FOR A RACK FOR SUPPORTING AN INTERCHANGEABLE RADIO TRANS- MITTER UNIT

Frederick H. Drake and John E. Johanson,
Boonton, N. J., assignors to Aircraft Radio Cor-
poration, Boonton, N. J., a corporation of New
Jersey

Application August 2, 1940, Serial No. 94,154

Term of patent 14 years

To all whom it may concern:

Be it known that we, Frederick H. Drake
and John E. Johanson, citizens of the United
States, residing at Boonton, county of Morris,
State of New Jersey, have invented a new, origi-
nal, and ornamental Design for a Rack for Sup-
porting an Interchangeable Radio Transmitter
Unit, of which the following is a specification,
reference being had to the accompanying draw-
ing, forming part thereof, and wherein:

Fig. 1 is a perspective view of the rack for

supporting an interchangeable radio transmitter
unit, showing our new design;

Fig. 2 is a plan view of the same;
Fig. 3 is a side elevational view; and
Fig. 4 is a rear elevational view.

We claim:

The ornamental design for a rack for sup-
porting an interchangeable radio transmitter
unit, as shown.
